(57) CLAIM

The ornamental design for a poncho, as shown and described.

DESCRIPTION

FIG. 1 is a left perspective view of a poncho showing our new design in an in-use configuration;

FIG. 2 is a right perspective view thereof;

FIG. 3 is a front view thereof;

FIG. 4 is a rear view thereof;

FIG. 5 is a left side view thereof;

FIG. 6 is a right view thereof; and,

FIG. 7 is a top view thereof.

The broken lines showing the remainder of the poncho and the unshaded regions therein are for environmental purposes only and form no part of the claimed design.
